L. P. KING.
Corn Sheller.

No. 237,755.

Patented Feb. 15, 1881.

Fig. 1.

UNITED STATES PATENT OFFICE.

LEICESTER P. KING, OF NEW CASTLE, INDIANA.

CORN-SHELLER.

SPECIFICATION forming part of Letters Patent No. 237,755, dated February 15, 1881.

Application filed December 11, 1880. (Model.)

To all whom it may concern:

Be it known that I, LEICESTER P. KING, a citizen of the United States, residing at New Castle, in the county of Henry and State of Indiana, have invented certain new and useful Improvements in Corn-Shellers; and I do hereby declare that the following is a full, clear, and exact description of the same, reference being had to the annexed drawings, making a part of this specification, and to the letters and figures of reference marked thereon.

Figure 1 is a top-plan view of my invention; and Fig. 2, a side elevation, partly in section.

The present invention has relation to certain new and useful improvements in that class of rotary corn-shellers in which yielding sheller-claws are connected to a horizontally-rotating gear-wheel, in addition to independent yielding holders for the cob arranged below the sheller-claws, to hold the cob from revolving while being operated upon.

The object of the invention is to provide means whereby the tension of the springs connected to the sheller-claws and the holders can be adjusted and regulated at pleasure, in addition to the peculiar construction of the holders and the various parts of the device, whereby a simple, practical, and effective corn-sheller is obtained at a comparatively small cost.

These objects I attain by the construction shown in the accompanying drawings, and hereinafter described.

In the drawings the frame, which is of cast metal, is composed of two sections, A B, each of which is formed with a leg or support, *a*. These sections A B have flanges *b*, by which they are connected together by bolts and nuts *c d*, the sections being also cast with box-sections *e*, to form a bearing, when together, for the shaft *f* of the bevel-gear wheel C, said shaft being provided with the usual crank-handle, D.

The sections A B are cast with grooves *g*, so that when the sections are bolted together an annular groove will be secured for holding the circumferential or annular shoulder *h* upon a horizontal gear-wheel, E, thereby supporting the same and admitting of its rotating horizontally within its groove-bearing by the rotation of the wheel C, the teeth of which

engage with the teeth upon the wheel E. The wheel E has arms *i* diametrically opposite each other, to which are pivoted the shanks *k* of the shelling-claws F. The arms *i* are cast with lugs *l*, through which pass the screw-threaded ends of rods *m*, and through holes in the shanks *k*, the ends of the rods having thereon screw-nuts *n*. A coiled spring, *p*, passes around the rods *m*, between the heads thereof and the lugs *l*, thereby the tension of the springs *p* being regulated by the adjustment of the nuts *n* upon the screw-threaded ends of the rods, to adapt the shelling-claws F to the various sizes of ears of corn, or for other purposes.

Jaws G, having a concave fluted surface upon their inner faces, bear against the cob or ear of corn to prevent it turning while the shelling-claws are being revolved. The shanks *r* of the jaws G are pivoted at their lower ends to lugs *s*, projecting from the inner sides of the legs or supports *a*, and below these pivotal points the shanks *r* terminate in stops *t*, which rest against the legs or supports and hold the jaws in position when closed, also preventing the springs *w* from pushing either jaw beyond the center or out of position, which is considered of great importance where yielding cob-holders are employed in this class of corn-shellers.

The lower ends of the springs *w* are secured to the shanks *r* of the jaws G, their upper ends being free, but bearing against set-screws *y*, said screws regulating the tension of the springs.

The yielding pressure of the jaws G upon the cob or ear of corn is regulated by the tension of the springs *w*, thereby making every provision for a complete and successfully operating device for shelling corn.

Having now fully described my invention, what I claim as new, and desire to secure by Letters Patent, is—

1. In a corn-sheller, the frame thereof composed of the sections A B, having grooves *g*, flanges *b*, and box-sections *e*, in combination with the shaft *f*, carrying wheel C, and the wheel E, having annular shoulder *h*, said wheel carrying yielding and adjustable shell-claws F, substantially as and for the purpose set forth.

2. In a corn-sheller, the pivoted shank *r*, having stops *t* formed upon their lower ends and carrying the concave corrugated jaws *G* upon their upper ends, and having the springs *w* attached to them, said springs being adjusted by means of set-screws *y*, substantially as and for the purpose set forth.

In testimony that I claim the above I have hereunto subscribed my name in the presence of two witnesses.

LEICESTER P. KING.

Witnesses:

C. D. CARTER,

ENOCH S. TAYLOR.
